TO ALUMINUM COMPANY OF AMERICA, OF PITTSBURGH, PENNSYLVANIA, A CORPORATION OF PENNSYLVANIA

WORK HANDLING MECHANISM

Application filed April 15, 1931. Serial No. 530,318.

This invention relates to work handling mechanisms employed in combination with rolling mills or similar fabricating means. The invention particularly relates to sheet handling mechanisms to be used when it is desired to produce, by rolling, a metal sheet product of high quality, free from surface blemishes and dimensioned within close tolerances.

10 An object of the invention is to provide an automatic sheet handling mechanism which will satisfactorily handle high grade metal sheet without injury to the sheet surface and reduce the required skill of the mill operator to a minimum.

Another object of the invention is to provide an automatic sheet handling mechanism which is of unitary design, and thus adaptable to various types of rolling mills.

20 A further object of the invention is to provide an automatic sheet handling mechanism which will increase the capacity of the rolling mill, to which it has been adapted, in the production of high quality rolled sheet.

25 A further object of the invention is to provide a mechanism which is readily adaptable, by virtue of various adjustable parts, to the careful handling of sheets of various lengths.

30 Other objects will present themselves on consideration of the following specification, appended claims, and accompanying drawings in which:

Fig. 1 represents in side elevation the preferred form of our sheet handling mechanism, portions of which have been broken away to more clearly show the construction;

Fig. 2 represents an end elevation of the mechanism as viewed from the right of Fig. 1;

35 Fig. 3 represents, in enlarged scale, a fragmentary elevation taken on the line III—III of Fig. 1;

40 Fig. 4 represents, in enlarged scale, a fragmentary view of the belt supporting pulleys;

Fig. 5 represents, in enlarged scale, a fragmentary top plan view, in partial section, of the carriage lead screw mechanism;

45 Fig. 6 represents a fragmentary view, in

side elevation, of the mechanism shown in Fig. 5;

Fig. 7 represents in diagrammatic form a modification of the mechanism comprising this invention;

55 Fig. 8 represents a further modification of the mechanism comprising this invention, wherein two such mechanisms, as shown in Fig. 1, are adapted to a two-high rolling mill.

60 Referring to the drawings, in which like reference characters denote similar parts, a preferred form of our mechanism is represented as comprising a main frame A, constructed from structural sections or the like, 65 in which is suitably mounted a carriage B for movement towards and away from a rolling mill to which the automatic sheet handling mechanism has been adapted. By means of this mechanism, material discharged from the rolling mill is conveyed by suitable endless belts into contact with a plurality of large diameter pulleys, rotatably supported in the aforementioned carriage B, which direct the sheet into a position accessible to the operator for subsequent rolling.

70 Referring to Fig. 1, the main frame A, which has been shown as constructed from standard structural shapes, but may be made from any other suitable shapes and material, comprises two oppositely disposed side panels 1 and 2 tied together by cross members to form a rigid structure. This main frame structure A is mounted upon wheels 75 3 adapted to run in countersunk channels 4 imbedded in the floor adjacent the discharge side of the mill to which the mechanism is adapted.

75 The carriage B, which supports a plurality of large diameter sheet returning and elevating pulleys 5, consists of two oppositely disposed side members 6 and 7 which are formed with extending legs 8, 9, 10, 11, and 12. Belt directing cylindrical pulleys 13, rotatably mounted upon centrally disposed shafts 14, are supported in the extending arms 8, 9, 10, and 11, the ends of the shafts 14 being suitably shouldered and threaded in such a manner that the side 100

frames 6 and 7 are tied together to form a rigid structure. A cylindrical pulley or idler roll 15 is similarly mounted in the forwardly extending arms 12 and differs 5 from pulleys or idler rolls 13 in that it is provided with a plurality of flanges 16.

Referring to Fig. 1, the large diameter pulleys 5, which may be constructed of any suitable material, although wood is preferable from the standpoint of weight, are of the split hub type adapted to be clamped to a central hollow cylindrical shaft member 17 which is rotatably mounted upon a central shaft 18 which is supported in the 15 side frames 6 and 7. The carriage B is equipped with flanged wheels 19 rotatably mounted on shafts projecting outwardly from the side frames 6 and 7, the wheels being positioned to run in the tracks formed 20 by the horizontal angles 20.

For adjusting the relative position of the carriage B with respect to the rolling mill, lead screws 21 are provided. These lead screws (Figs. 1, 5, and 6) are oppositely disposed beneath the flanges of the lower horizontal track angles 20 and are undercut at their ends below the threads, which undercut portions are encased in the bearing blocks 22 supported from the lower track angles 20. Miter gears 23 are fixedly mounted on the lead screws 21 and are adapted to mesh with miter gears 24 fixedly mounted upon the shaft 25 which is rotatably mounted in angular bearing brackets 26 supported on the main frame A.

The rotation of the shaft 25 by a reversible driving means, such as the motor 27, acting through the sprocket and chain drive 28, rotates, through the inter-meshing miter gears 23 and 24, the lead screws 21 which are in threaded engagement with the nuts 29 supported on the carriage side frames 6 and 7, thus moving the carriage B towards and away from the rolling mill. Limit stop switches 30 are so positioned on the main frame A as to be actuated by projections 31 on the carriage B to stop the motor 27 as the carriage reaches its extreme positions towards or away from the rolling mill.

Systems of endless conveyor belts 32 and endless hold-down belts 33 are employed in association with the large diameter pulleys 5. These belts are equal in number to the pulleys 5, there being six of each in the preferred mechanism. The belts are composed of canvas or some other suitable material which will not scratch or otherwise impair the surface of the sheet being handled. The hold-down belts 33 are positioned in peripheral contact with the large diameter pulleys 5 and cylindrical pulley 15, the flanges 16 of which are provided to guide the belts. Belts 32 are driven by pulleys 34 which are supported upon the shaft 35 rotatably mounted in suitable bearings positioned at the forward end of the main

frame A adjacent the rolling mill. These belts 32 extend horizontally and rearwardly into arcuate contact with pulleys 5 and thence into arcuate contact with the cylindrical pulleys or idler rolls 13 to complete their endless lengths. The belts 32 are supported at suitable intermediate points in the horizontal plane by means of guide rollers 36 of fiber or other suitable material, as shown to best advantage in Fig. 4. Individual belt tightener pulleys 37, rotatably supported in suitable brackets 38, are adapted to slide in arcuate contact with endless belts 32 upon inverted channels 39 under a motivating force applied by manipulation of the lead screws 40 which extend through threaded holes in the brackets 38. These lead screws 40 are rotatably supported at one end in the cross angle 41, and at the other end in a cross member of the main frame A.

A work receiving table or platform C in the form of guides 42 and 43 is adapted to receive the sheet which is conveyed from the discharge side of the rolling mill and raised to an elevated position by means of the pulleys 5 in combination with the conveyor belts 32. The guides 42 are composed of fiber strips 42a mounted on edge upon inverted T sections disposed between the belts 32 and rotatably or loosely supported at their rear ends upon a bar or shaft 44 mounted in lugs protruding from the carriage arms 8. The rearward portions of the guides 42 are curved downwardly so that they will always assume a position below the level of the sheet coming off the pulleys 5 for all positions of the carriage B, and the forward ends of the guides 42 are supported within the guides 43 which consist of fiber strips 43a mounted on edge upon flanges of inverted channel sections. The guides 43 are arranged in alignment with guides 42 and are rigidly supported by angular braces 45 and the main frame A. Referring to Fig. 3, the upper edges of the guide strips are rounded to insure against any abrasion of the sheet, and the telescopically arranged mounting permits guides 42 to slide into guides 43 as carriage B is translated. Fiber rolls 46 rotatably mounted at the forward ends of the guides 43 facilitate the transfer of returned material to a position in front of the rolling mill.

In the operation of our automatic sheet handling mechanism, the main frame A is positioned in proper relationship with the rolling mill, to which it has been adapted, rail clamps 51 being employed to secure the mechanism in place. A suitable motor control panel for controlling the carriage translating motor 27, and also a variable speed motor 47 directly connected to an adjustable speed reducer 48 which is sprocket and chain connected to the drive shaft 35, is provided on the operator's side of the mill. The car-

riage B is positioned so that the length of belts 32 as measured from the drive pulleys 34 to their points of contact on the large diameter pulleys 5 is only slightly longer than the metal sheet desired to be produced. We consider it desirable, in the production of high quality sheet, that the sheet be completely discharged from the mill rolls before it is embraced between the belts 32 and 33, which procedure eliminates stretching of the sheet, or other deleterious conditions. Furthermore, the hold-down belts 33 provide a positive means of clamping two or more sheets together in pack rolling, thereby eliminating the possibility of scratching the superimposed surfaces of the contacting sheets because of slippage.

The sheet, on leaving the mill rolls, is directed onto the conveyor belts 32 by the stripper fingers 49 and the upper guides 50, and conveyed, in the direction indicated by the arrow, to where it is embraced between the hold-down belts 33 and conveyor belts 32 which act in combination with the large diameter pulleys 5 to elevate and discharge the sheet upon the platform C formed by the guides 42 and 43. The location of the topmost pulley 13 is such that the sheet comes off the pulleys 5 substantially horizontal when discharged on the guides 42.

The sheet comes to rest on the platform C where it may be inspected by the operator and drawn over the rollers 46 into position for a subsequent pass through the mill. As the sheets increase in length, the carriage B is translated away from the mill rolls. It is also possible to increase or decrease the interval of time of returning the sheet, and, therefore, the time interval necessary for inspection, by simply manipulating the position of the carriage B and the speed of the motor 47. Two modifications of our sheet handling mechanism are shown in diagrammatic form in Figs. 7 and 8. In the embodiment of our mechanism shown in Fig. 7, the elevating and reversing pulleys 52 are stationary with respect to translation towards or away from the rolling mill. A plurality of endless belts 53 are directed in arcuate contact with the pulleys 52 and the pulleys 54, 55, 56, and 57 to comprise a conveying and elevating mechanism.

A second system of endless belts 58 are arranged in contact with the elevating and reversing pulleys 52 and also the pulleys 59, 60, 61, and 62. These belts 58 act as hold-down belts in conveying sheet material from the discharge side of the rolling mill into engagement with pulleys 52, and are of prime importance in pack rolling. Pulleys 61 and 62 are suitably mounted for adjustment to any position between their full line and dotted line positions, which construction, in combination with stationary guide members 63 of fiber or other suitable mate-

rial, the top surfaces of which are arranged slightly below the line of the belts 58, makes it possible to retard the return of the rolled material in accordance with the position of the pulleys 61 and 62.

This mechanism is shown as used in conjunction with a two-high mill, but it will be readily understood that it could be applied to a three-high mill by arranging the discharge side of belts 58 in line with the return pass, in which case the retarding guide members 63 would be eliminated.

Referring to Fig. 8, a further embodiment of our invention is shown. Herein two of the mechanisms, described as being the preferred form of this invention, are arranged one on either side of a rolling mill and are connected together by means of a suitable conveyor. As indicated by the arrows, the sheet is fed into the mill from a suitable table 64 and is discharged upon conveyor belts 65 whence it is elevated and discharged by pulleys 66 upon a conveyor 67. The conveyor 67, which replaces the guides 42 and 43 in the preferred form of our mechanism, conveys the sheet into a similar mechanism on the feed side of the mill where it is returned between the belts 68 and the pulleys 69 to the table 64. By adjusting the relative positions of the carriages supporting the pulleys 66 and 69, the rolled sheet may be returned to the operator in position, on the table 64, for inspection and subsequent rolling.

Since it is obvious that various changes may be made in the above-described specific details without departing from the nature or scope of this invention, this application is not to be considered limited thereto except as defined in the appended claims.

What we claim is:

1. A sheet manipulator comprising a main frame, a drive shaft rotatably mounted on said frame, a movable carriage supported upon tracks in said main frame, sheet elevating and conveying pulleys mounted in said carriage, idler rolls rotatably mounted in said carriage, and a plurality of endless belts in association with said pulleys and idler rolls in clamping relationship with said sheet elevating and conveying pulleys.

2. A sheet handling mechanism comprising a main frame, a movable carriage supported upon said frame, nuts fixedly mounted on the side frames of said carriage, horizontal lead screws threaded in to said nuts, bearings for said lead screws mounted on the main frame, a pair of gears fixedly mounted upon the lead screws in mesh with a pair of gears fixedly mounted upon a shaft rotatably supported on the main frame, and means for driving said second-named shaft to impart movement to said carriage.

3. An automatic sheet handling mech-

- anism comprising a plurality of endless belts directed over drive pulleys and idler rolls, the endless belts arranged in arcuate contact with a plurality of sheet elevating and reversing pulleys, and a plurality of endless hold-down belts directed over the said sheet elevating and reversing pulleys and an idler roll disposed in front thereof. 5 70
4. An automatic sheet handling mechanism comprising a main frame, a movable carriage mounted thereon, conveyor belts and pulleys arranged in association with said carriage for elevating and reversing sheet material, and a receiving table composed of a plurality of guides telescopically arranged to increase or decrease in length in accordance with the movement of the carriage. 10 75
5. An automatic sheet handling mechanism comprising a main frame, a movable carriage mounted thereon, conveyor belts and pulleys arranged in association with said carriage for elevating and reversing sheet material, individual belt tightener pulleys, and a receiving platform. 20 80
6. In combination with a three-high rolling mill, automatic sheet handling apparatus comprising a plurality of endless conveyor belts in association with adjustable sheet elevating and reversing pulleys, said conveyor belts being arranged to carry sheet from the pass formed between the bottom and middle roll and discharge said sheet into the pass formed between the top and middle roll. 25 85
7. In combination with a rolling mill, means for conveying material away from the discharge side of said mill, adjustable rotating means for elevating said sheet, separate conveying means for conveying said material over the top of said mill, and adjustable rotating means for lowering and discharging said material in position for a subsequent rolling operation. 30 90
8. A mechanism of the character described, comprising a main frame in combination with a movable carriage mounted for reciprocatory movement thereon, a receiving platform, a conveyor system mounted on said frame, said conveyor system being adapted to cooperate with said carriage to deliver material to said receiving platform. 40 95
9. A mechanism of the character described, comprising a main frame, a movable carriage mounted in said main frame, a stationary receiving platform, a sheet reversing mechanism mounted in said carriage, said sheet reversing mechanism being adapted to deliver material in reversed position to said stationary receiving platform. 45 100
10. A sheet manipulator comprising a main frame and a carriage movably mounted therein, a material receiving platform, 50 105
- 60 sheet elevating and reversing means mount- 110
- 65 ed in said carriage, a conveyor system in association with said main frame and said elevating and reversing means, said conveyor system being adapted to cooperate with said elevating and reversing means to deliver material in reversed position to said material receiving platform. 115
